UNITED STATES PATENT OFFICE.

JOHN GEORGE MENGEL, JR., OF BALTIMORE, MARYLAND.

DESIGN FOR A FONT OF PRINTING-TYPE.

SPECIFICATION forming part of Design No. 15,655, dated December 30, 1884.

Application filed November 25, 1884. Term of patent 7 years.

To all whom it may concern:

Be it known that I, JOHN GEORGE MENGEL, Jr., a citizen of the United States, residing at Baltimore, in the county of Baltimore and State of Maryland, have invented and produced a new and original Design for a Font of Printing-Type; and I do declare the following to be a full, clear, and exact description of the same, reference being had to the accompanying impression, which forms a part of this specification.

In this font each letter, both large and small, and the punctuation-marks are shown as being placed on a solid background, which has a conventional ornamental border both above and below it. The capital letters and a few of the small letters partly conceal the borders, as shown.

The effect of a word or words printed with this type is that of a solid bordered background with the letters imprinted thereon.

This type is especially designed for names, titles, &c., and terminal and initial types are provided, which may embody the letter-border or other conventional designs, as shown. 25 The letters are composed of closely-placed horizontal lines, with light shading on the upper end and left-hand side, which contrasts with the solid background. A portion of the letters are ornamented with small spirals, as 30 shown.

I claim as my invention—

The design for a font of printing-type, as shown and described.

In testimony whereof I affix my signature in 35 presence of two witnesses.

JOHN GEORGE MENGEL, JR.
